HANDLE FOR CABINETS AND THE LIKE

La Verne E. Clayton, Rockford, Ill., assignor to Amerock Corporation, Rockford, Ill., a corporation of Illinois

Filed May 4, 1964, Ser. No. 79,811

Term of patent 14 years

(Cl. D10—8)

FIG. 1 is a front elevational view of a handle for cabinets wherein my design is embodied in a knob;

FIG. 2 is a side view of FIG. 1;

FIG. 3 is a sectional view taken along line 3-3 of FIG. 1;

FIG. 4 is a front elevational view of a handle for cabinets wherein my design is embodied in a pull;

FIG. 5 is a side view of FIG. 4;

FIG. 6 is a sectional view taken on line 6-6 of FIG. 4.

The dominant features of my design reside in the portions shown in full lines.

This is a continuation-in-part of my copending application Serial No. D. 74,945, filed May 20, 1963 now abandoned.

I claim:

The ornamental design for a handle for cabinets and the like, substantially as shown and described.
